United States Patent Office

Des. 201,219
Patented May 25, 1965

201,219

BOTTLE

James A. Shepler, Toledo, Ohio, assignor to Owens-Illinois Glass Company, Toledo, Ohio, a corporation of Ohio

Filed Oct. 21, 1964, Ser. No. 82,276

Term of patent 14 years

(Cl. D58—6)

FIG. 1

FIG. 2

The back and side not shown are the same as the front and side shown. The characteristic features of this design reside in the configuration shown in full lines on the drawing.

I claim:

The ornamental design for a bottle, substantially as shown and described.
